UNITED STATES PATENT OFFICE.

FRANK L. WOLFE, OF MEDFORD, MASSACHUSETTS, ASSIGNOR TO CROSBY STEAM GAGE AND VALVE COMPANY, OF BOSTON, MASSACHUSETTS, A CORPORATION OF MASSACHUSETTS.

WHISTLE-VALVE.

No. 873,822.

Specification of Letters Patent.

Patented Dec. 17, 1907.

Application filed December 5, 1905. Serial No. 290,416.

To all whom it may concern:

Be it known that I, FRANK L. WOLFE, a citizen of the United States, and a resident of Medford, in the county of Middlesex and State of Massachusetts, have invented certain new and useful Improvements in Whistle-Valves, of which the following is a specification.

My invention relates to whistle valves and its object is to provide means for automatically operating such valves and automatically recording the passage of steam through the outlet chamber of the valve into the whistle bell, and the time of such passage.

15 It is an improvement upon my invention described in Letters Patent No. 787,422 dated April 18, 1905; and also upon another invention for which I have applied for Letters Patent by an application filed December 1, 1905 Serial No. 289,878.

It is illustrated by the accompanying drawings in which—

Figure 1 is a vertical section of the whistle valve. Fig. 2 is a plan view of the clock. 25 Fig. 3 is an elevation of the electro magnet on line 3—3, of Fig. 2.

Similar characters refer to similar parts throughout the several drawings.

1 is the whistle bell. 30 2 is the whistle bowl threaded at its base for attachment to the steam, or any other fluid reservoir and divided into two communicating chambers; the inlet chamber 3 and the outlet chamber 4. Seated in chamber 3 is the valve 5 operated by the piston 6 located in the cylinder 7 laterally projected from the outlet chamber 4, and having passages 8 leading to the open air and other passages 9 leading to the cylinder 10 laterally projected from inlet chamber 3. In the inlet chamber 3 is also seated the spring actuated valve 11 with its stem 12 arranged in the cylinder 10 which may be operated mechanically by the lever 13 fulcrumed at 14 on 45 the outer wall of cylinder 7.

Projected from the inlet chamber 3 is the cylinder 15 with a reduced inner portion 16, a larger middle portion 17 with passages 18 leading therefrom to the inlet chamber 3 and 50 a still larger outer portion 19 which constitutes the cylinder proper with the passage 20 leading therefrom to the inlet chamber 3. In the outer portion 19 of the cylinder 15 is located the balanced piston 21 having the 55 tubular grooved stem 22 in sliding contact

with the middle portion 17 of the cylinder 15. This piston 21 engages loosely the outer portion 19 of the cylinder 15 thereby permitting the steam from the inlet chamber 3 to surround it and becoming balanced in said steam. The valve 11 has a second valve stem 23 which passes through and is in sliding contact with the inner portion 16 of the cylinder 15, the piston stem 22 and piston 21, and is furnished on its outer end with the adjustable nut 30. On the valve stem 23 is arranged the spring 25 confined between shoulders on the valve 11 and on the cylinder 15.

Projected from the cylinder 15 is the diaphragm chamber 26 with a passage leading from one to the other, through which passage extends the valve stem 28 of the spring actuated valve 29 seated in said cylinder 15.

Passages 24 lead from the diaphragm 75 chamber 26 to the open air. In this diaphragm chamber are arranged the diaphragm 31 and the spring 32. The diaphragm 31 rests upon the annular shoulder 33 in contact with the outer end of the valve 80 stem 28, and is held in place by the threaded ring 34.

Projected from the diaphragm chamber 26 is the casing 35 in which is arranged the electro magnet 36 with its spring actuated armature 37. Fixed to said armature is the stem 38 which passes through and is in sliding contact with the said casing 35 and extends into the diaphragm chamber, and has its inner end in contact with said diaphragm 31 opposite the outer end of the valve stem 28. The wires 39, 39^a pass through the insulator box 40 and stuffing box 41 into the clock—Fig. 2.

Projected from the outlet chamber 4 is the 95 diaphragm chamber 42 with the passage 43 leading thereto from said outlet chamber 4. In the passage 43 is seated the spring actuated leak valve 44. On an annular shoulder 45 of the diaphragm chamber 42 rests the diaphragm 46 held in place by the threaded ring 47 which engages the threaded wall of the diaphragm chamber 42. The threaded hub 48 engages the said threaded wall of the diaphragm chamber acting as a jam nut on 100 the threaded ring 47. Extending through this hub 48, and in free sliding contact therewith, is the spring actuated plunger 49 with its inner end in contact with said diaphragm 46, and having mounted in its outer end the 110

fiber tip 50 in contact with the contact spring 51 which, with the corresponding contact spring 51^a, is mounted on the fiber ring 52 which fits into the diaphragm chamber 42 and encircles the central portion of the hub 48. The contact springs 51, 51^a are engaged by binding screws from which the wires 53, 53^a lead into the clock—Fig. 2. In this clock the gears are such that the central arbor 54 rotates once in four hours. Mounted on this arbor is a toothed wheel 55 whose teeth successively engage the spring 56 normally in contact with the adjustable contact screw 57 mounted on the insulator fiber block 58 mounted in said case, to which block the wires 39, 39^a lead, the wire 39 being connected by the binding nut 59 with said spring 56, and the wire 39^a being connected by the binding nut 59^a with the adjustable screw 57 whose inner end normally contacts with the spring 56. The wires 53, 53^a connect with the electro magnet 64 disposed within the clock case with its spring actuated armature 65 having an arm 66 pivoted to the arm 67 fixed to the shaft 68 mounted in the clock case, and having fixed to its upper end the pencil arm 69 carrying the pencil 70 and the arm 71 carrying a pencil platform 72. On the arbor 54 is mounted the rotary chart support 73 on which rests the chart 74 held in place by the washer 75 and thumb nut 76. This chart rests also upon the annular support 77.

This device, which may be used for recording the operation of the whistle valve under any conditions, is particularly useful upon vessels where whistles are required to be sounded at certain intervals, for instance during a fog; and the chart in the drawing is arranged to rotate once in four hours, as just stated, or during the usual watch on vessels. Of course any fluid other than steam may be used with the whistle valve.

The operation of the device is as follows: The whistle valve being attached to a steam boiler, steam fills the inlet chamber 3, the passages 18 and 20, and the cylinder 15, pressing equally on the inner and outer surfaces of the piston 21, the valves 5, 11, and 29 are seated; the valve stem 23 has a very slight longitudinal play so as to insure the seating of the valve 11. The valve stem 28, the diaphragm 31 and armature stem 38 are in contact. When the electric circuit 39, 39^a is closed the spring 56, being in contact with the screw 57, the armature forces the valve 29 from its seat, compressing the spring 32 and extending the spring 38^a, and permitting steam to escape from cylinder 15 to the open air. The balanced piston 21 is forced by the steam outwardly, unseating the valve 11 and compressing the spring 25. The steam escapes into the cylinder 10 thence through the passages 9 into that part of the cylinder 65 above the piston 6. The pressure of the

steam upon the piston being practically the same as that of the steam in the inlet chamber, and the surface of the piston being greater than the surface of the valve 5, this pressure will force the valve from its seat and allow steam to escape from the inlet chamber into the outlet chamber 4 and thence upward through the whistle bowl 2 into the whistle bell and sound the whistle, also into the passage 43 and thence into the cylinder 42 against the diaphragm 46 thrusting it outwardly, thereby operating the plunger 49 and bringing the contact springs 51, 51^a into contact, closing the electric circuit 53, 53^a, operating the pencil arm 69, and moving the pencil 70 upon the rotating chart 74.

The gear 55 on the arbor 54 carries the spring 56 out of contact with the screw 57, thereby opening the circuit 39, 39^a and the valves 29 and 11 return to their seats, forced thereto by the steam pressure assisted by the springs 25, 32 and 38^a. The steam remaining in the cylinder 10, passages 9 and space above the piston 6 in cylinder 7 instantly escapes through the passages 8 into the open air, thus removing the pressure from the piston 6 and allowing the valve 5 to be forced to its seat by the pressure of steam in the inlet chamber 3; thus cutting off the supply of steam to the outlet chamber 4, to the whistle bowl and to the diaphragm chamber 42, thus permitting the spring actuated plunger to move inwardly and separate the springs 51 and 51^a thereby opening the circuit 53, 53^a permitting the armature 65 to return the pencil 70 to its starting point; and so the operation is repeated and the whistle sounded as the teeth of the gear 55 successively make and break the contact of the spring 56 with the screw 57, as just described. The circuit 39, 39^a may be opened and closed by pressing a button if desired.

Having described my invention, what I claim and desire to secure by Letters Patent is—

1. In a system of the character described a whistle valve with an inlet chamber and seated therein a valve, an outlet chamber communicating with said inlet chamber by a passage controlled by said valve, mechanism for opening and closing said valve, an electric circuit including and operating said mechanism, a clock in said circuit with mechanism for opening and closing said circuit, mechanism operated by steam passing through said outlet chamber, a second electric circuit including said last named mechanism and opened and closed thereby, and means arranged in said clock and included in said second circuit and operated thereby for recording such opening and closing of said second circuit; substantially as described.

2. In a system of the character described a whistle valve with an inlet chamber and seated therein a valve, an outlet chamber

communicating with said inlet chamber by a passage controlled by said valve, mechanism for opening and closing said valve, an electric circuit including and operating said mechanism, a clock in said circuit with mechanism for opening and closing said circuit, mechanism operated by steam passing through said outlet chamber, a second electric circuit including said last named mechanism and opened and closed thereby, a rotary chart support in said clock operated by said clock mechanism, a rotary pencil in said clock and included in said second circuit and operated thereby for recording such opening and closing of said second circuit; substantially as described.

3. In a system of the character described a whistle valve with an inlet chamber and an outlet chamber connected by a valve controlled passage, such valve, mechanism for operating said valve, an electric circuit including and operating said mechanism, a clock in said circuit with mechanism for opening and closing said circuit, mechanism operated by steam passing through said outlet chamber, a second electric circuit including said last named mechanism and opened and closed thereby, and means arranged in

said clock and included in said second circuit and operated thereby for recording such opening and closing of said second circuit; substantially as described.

4. In a system of the character described a whistle valve with an inlet chamber and an outlet chamber connected by a valve controlled passage, such valve, mechanism for operating said valve, an electric circuit including and operating said mechanism, a clock in said circuit with mechanism for opening and closing said circuit, mechanism operated by steam passing through said outlet chamber, a second electric circuit including said last named mechanism and opened and closed thereby, a rotary chart support in said clock operated by said clock mechanism, a rotary pencil in said clock and included in said second circuit and operated thereby for recording such opening and closing of said second circuit; substantially as described.

In testimony whereof I have affixed my signature, in presence of two witnesses.

FRANK L. WOLFE.
